UNITED STATES PATENT OFFICE.

ALBERT G. NYGREN, OF MILWAUKEE, WISCONSIN.

DESIGN FOR A LIGHT FIXTURE.

61,377.

Specification for Design. Patented Aug. 15, 1922.

Application filed December 8, 1921. Serial No. 521,040. Term of patent 3½ years.

To all whom it may concern:

Be it known that I, ALBERT G. NYGREN, a citizen of the United States, residing at Milwaukee, in the county of Milwaukee and State of Wisconsin, have invented a new, original, and ornamental Design for a Light Fixture, of which the following is a specification, reference being had to the accompanying drawing, forming part thereof.

The drawing illustrates a perspective view

of a light fixture made in accordance with my invention.

I claim:

The ornamental design for a light fixture, as shown.

In testimony that I claim the foregoing I have hereunto set my hand at Milwaukee, in the county of Milwaukee and State of Wisconsin.

ALBERT G. NYGREN.
